(57) **CLAIM**

We claim the ornamental design for a modular sleeping unit, as shown and described.

DESCRIPTION

FIG. 1 is a front perspective view of a modular sleeping unit showing our new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a cross-sectional view at 7-7 in FIG. 6 showing the rear internal wall;

FIG. 8 is a cross-sectional view at 8-8 in FIG. 6 showing the front internal wall and the internal elements that are attached to the wall that has been cut away are omitted from the view for ease of disclosure;

FIG. 9 is an internal perspective view thereof facing the left internal wall of the modular sleeping unit showing the desk in an open position; and,

FIG. 10 is an internal perspective view thereof facing the right internal wall of the modular sleeping unit showing the desk in an open position.

The broken lines shown in FIGS. 3-8 illustrate portions of the modular sleeping unit that form no part of the claimed design.
